FRANCIS A. J. FITZ GERALD, OF NIAGARA FALLS, NEW YORK, ASSIGNOR TO IMBERT PROCESS COMPANY, OF NEW YORK, N. Y., A CORPORATION OF NEW YORK.

METHOD OF PROTECTING RESISTERS OF ELECTRIC FURNACES.

950,905.

Specification of Letters Patent.

Patented Mar. 1, 1910.

Application filed September 1, 1909. Serial No. 515,711.

To all whom it may concern:

Be it known that I, FRANCIS A. J. FITZ GERALD, a subject of the King of Great Britain, and a resident of Niagara Falls, in the county of Niagara and State of New York, have invented certain new and useful Improvements in Methods of Protecting Resistors of Electric Furnaces, of which the following is a specification, reference being had to the accompanying drawings, forming a part hereof.

The object of the invention is to effectively prevent the entrance of air into the heating or melting chamber of electric furnaces, or around the resister, for the purpose of protecting the latter from the detrimental effects of the contained oxygen and thus enhancing the endurance and efficiency of the resister.

It is well known that where carbon resistors are employed in electric furnaces, the effect of the presence of air and other active gases in the melting chamber, where the resister is exposed, is to actively attack and disintegrate the carbon. For this reason, it is particularly desirable to have some method of checking the action of the gases upon the carbon; and the present invention, broadly considered, contemplates the introduction, more or less continuously, of an inert gas, such as "producer gas," into the melting chamber around the resister, such gas largely displacing any active gas which may have been generated therein and effectively checking the entrance of air. Moreover in accordance with the invention, the introduction of inert gas may be controlled manually, as visual observation may dictate, or automatically according to the relation of pressures within and without; or, in fact, the inert gas may be delivered gradually to the furnace substantially without interruption.

Referring to the drawings: Figure 1 shows, in vertical section, an electric furnace provided with means for practicing the invention, and, Fig. 2 is also a sectional view, showing a form of regulating or controlling means which may be used in carrying out the invention.

In Fig. 1, the carbon resister is shown at D, having terminals e and e' and disposed above the bath in the melting chamber c. The furnace, in the present instance, is provided with a cover b and a charging open-

ing g. The inert gas may be forced in through a refractory tube or opening m and the amount of gas introduced may be regulated by any suitable means until sufficient gas enters to maintain a test flame, as 60 through a duct n in the cover b. The quantity of gas necessary to thus exclude the air is, as to its cost, commercially negligible; and ordinarily, the rate of its delivery will vary according to conditions. Thus, in first 65 starting a furnace, raising the temperature from normal to high, or when opening the furnace for inspection or charging, the quantity will be maximum, whereas when the internal heat-pressure exceeds that of 70 the external air-pressure no gas whatever would be required.

Advantage can be taken of the foregoing conditions to regulate or control the supply of inert gas automatically. Thus, as in Fig. 75 2, a check valve may be provided in the delivery tube which shall comprise the following elements: A main casing 1, having a suitable head 2 in which is a cross strut 3 acting as a bearing for a spindle 4 of a pup- 80 pet valve h, preferably formed with a conical contact surface 5 to impinge upon a corresponding surface 6 formed within the casing. In the position assumed in the drawing, the valve is open, leaving a narrow 85 circumferential space, as 7, which connects the chamber 8 with the chamber 9. The area of the valve should be relatively large as compared with that of the connecting pipes. Now, if the inert gas enters 90 in the direction of the arrow, it will pass around the circumferential opening of the valve and thence to the furnace; but if the heat-pressure from the furnace exceeds that of the gas, then the flow will be re- 95 versed, and the valve will be forced to its seat, as indicated in dotted lines 10, while the heat-flow will terminate in the valve chamber. The axis of the valve is prefer- 100 ably set at an angle to the horizontal, as shown, so that the valve will, by gravity, remain open. Obviously, this condition may be neutral or reversed, but the object of the disposal shown is to insure an immediate flow, or as it were, a slight static head, of the 105 inert gas to or in the furnace chamber.

It has been ascertained by practical demonstration that the method herein described operates thoroughly well and that the endurance and efficiency of electric carbon re- 110

sisters can thus be increased to an extent not hitherto deemed possible. While it is manifest that a small amount of carbon monoxid gas will result from the introduction of the 5 "producer gas", this will be far less harmful, even in the most delicate of commercial metallurgical operations, than the oxygen or the carbon dioxid gas which would otherwise ordinarily be present.

10 I claim as my invention:

1. The method of protecting the resister of an electric furnace from oxidizing or other active gases which consists in introducing an inert gas into the melting chamber and around the resister.

15 2. The method of protecting the resister of an electric furnace from oxidizing or other active gases, which consists in surrounding the resister with an inert gas.

3. The method of protecting the resister 20 of an electric furnace from oxidizing or other active gases, which consists in introducing an inert gas continuously into the melting chamber and around the resister.

4. The method of protecting the resister 25 of an electric furnace from oxidizing or other active gases, which consists in introducing an inert gas into the melting chamber and around the resister automatically according to the pressure in the melting 30 chamber.

This specification signed and witnessed this 26th day of August, A. D., 1909.

FRANCIS A. J. FITZ GERALD.
